(57) **CLAIM**

The ornamental design for a lid for basket for air fryer, as shown and described.

DESCRIPTION

FIG. 1 is a perspective view of the lid for basket for air fryer showing our new design;

FIG. 2 is another top perspective view thereof, shown without environment;

FIG. 3 is a rear elevational view thereof, the front view being identical;

FIG. 4 is a right side elevational view thereof;

FIG. 5 is a left side elevational view thereof;

FIG. 6 is a top plan view thereof; and,

FIG. 7 is a bottom plan view thereof.

The broken lines shown in the drawings are for illustrative purposes only and form no part of the claimed design.
